PIANO ACTION

Wilbur W. Waters, Newington, Conn.

Application December 13, 1952, Serial No. 325,784

6 Claims. (Cl. 84—240)

1

This invention relates to piano actions and pertains more particularly to an action especially suitable for use in a restricted space such as in a spinet or small upright piano.

One object of the invention is to provide an action simulating that of a grand piano which is exceedingly compact, thereby enhancing the appearance of the piano in which such action is installed by permitting more graceful styling. Fortunately, there is also effected a saving of material inasmuch as the piano case may be stepped-in immediately below the compact action.

In addition to rendering the action more concentrated, another object of the invention is to provide an action having several improved mechanical features. In this connection, the power derived from the operation of the piano key is applied directly to the hammer until the hammer head is only one-eighth inch from the sounding string as in conventional actions. However, it is within the purview of the instant invention to have an additional impetus applied to the hammer immediately preceding the disengagement of the jack from the hammer butt, thereby increasing the force with which the hammer strikes the string. Further, by virtue of the arrangement envisaged, there is no tendency for the jack to deflect from its power-applying position until its release from the hammer butt is desired, for provision is made for maintaining a positive engagement between the jack and the hammer butt during this period. Also, in accordance with the teachings of the invention, it is possible to utilize a full-size hammer shank such as those used in large uprights, thus assuring, in conjunction with the above-mentioned features, that a full, heavy blow will be applied to the sounding string. More specifically, it is possible to employ a hammer shank having a length of four inches without materially affecting the compactness of the action, since the jack extends in generally the same direction as the hammer shank.

Another object of the invention is to provide a piano action having a very fast repetition, each key and its associated mechanism being automatically conditioned for a prompt successive operation thereof. To accomplish this end, it is within the teachings of the invention to store up sufficient energy on the rebound movement of the hammer just prior to the engagement of the catcher with the back check so that upon release of the back check from the catcher a forward movement toward the sounding string is precipitated permitting the jack to be quickly re-engaged with the hammer butt for the next operation of the piano key.

2

A still further purpose of the invention is to provide a piano action of the foregoing character which comprises a relatively few number of parts, which is rugged, and which may be inexpensively manufactured. Also, it is planned that such adjusting members as the regulating and capstan screws will be readily accessible for facile manipulation from a vantage point above the action, without interference from other parts and without having to remove the action from its mounting.

Yet another object of the invention is to eliminate any need for the conventional bridle strap and bridle wire.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the drawings:

Figure 1 is an end view of the action in its rest position with parts of the frame shown in section;

Figure 2 is a view similar to Figure 1 after the key has been fully depressed; and

Figure 3 is an intermediate view shortly after key has been released and the parts are returning toward their rest position.

Referring in detail to the drawings, there is shown a piano sounding string 10 adapted to be struck when a conventional key 12 is depressed; the key 12 having a somewhat downwardly extending end 14 which underlies a capstan screw 16 carried at one end of a whippens 18. By having the end 14 offset downwardly, the entire action may be placed at a lower elevation while maintaining the standard keyboard height. The key 12 is fulcrumed for rocking movement in the usual fashion about a balance rail 20. The whippens 18, on the other hand, is pivotally mounted to an action bracket 22 by means of a pivot pin 24 supported by an upstanding post 26. As is conventional in piano actions, the action bracket 22 also serves as a support for a damper head 28, there being an upstanding post 30 carrying a pivot arm 32 upon which the damper head is surmounted. Extending from the pivotal arm 32 is a spoon element 34 which is engageable by one end of the whippens 18 to cause withdrawal of the damper head 28 from the sounding string 10 when the whippens 18 is rotated counter-clockwise by the depressing of the key 12, thus providing a sustained tone when the string is struck by a hammer present.

ly to be referred to. The damper head 28 can also be actuated by a damper rod 36 which has an offset 38 so positioned as to be engageable with one end of the pivotal arm 32 when the damper rod 36 is pivoted as by the sustaining pedal associated with the piano. Since the utilization of damper heads is old and well-known in the art, it is believed that the function of the damper head 28 will be readily understood without further explanation as this feature forms no part of the instant invention.

Intermediate the capstan 16 and the pivot pin 24 of the whippen is pivotally carried a jack 40, the jack being disposed in a slot 41 with a pin 42 providing the desired articulative action. The upper end of the jack 40 has a lateral projection 44 and the lower end is substantially J-shaped as designated by the reference number 46, the J-shaped portion 46 terminating in an upwardly directed hooked extremity 48. Positioned above the projection 44 is a hammer rail 50 carrying a downwardly extending regulating screw 52, the purpose of which is to cause rotation of the jack about its pivot point at the desired moment. Biasing the jack 40 in a clockwise direction is a jack spring 54, the express purpose of which will be more readily understood as the description progresses.

A hammer assembly 55 including a hammer head 56, a shank 58, and a butt 60 is pivotally mounted on an upstanding post 62 by means of a pivot pin 64, and, as in conventional piano actions, the hammer assembly is situated so as to have the hammer head 56 strike the sounding string 10. Serving as a biasing means to urge the hammer assembly away from the string 10 is a hammer spring 66, it being mounted at one end to the action bracket 22 and having its other end in engagement with a portion of the butt 60 above the pivot pin 64. A generally upwardly directed notch 68 is provided in the lower end of the butt 60 in an offset relation with the pivot pin 64, the notch 68 being formed in part by a downwardly inclined nose 70 covered with a suitable cushioning material for the jack such as felt surfaced with thin leather.

Extending laterally from the butt 60 is an elongated spring member 72, which will hereinafter be referred to as a repetition spring, so configured that an arcuate section 74 thereof will engage the bottom of a slot 76 contained in the jack 40 during a portion of the jack's rotative travel. In order to better illustrate the cooperation the spring 72 has with the slot 76, a section of the jack bordering the slot has been removed in each figure. Actually the slot 76 could, if desired, be a rectilinear notch against the bottom of which the spring 72 would then bear.

A catcher 78 may be integral with the butt 60 or if desired it may extend from the hammer shank 58, and cooperating with the catcher 78 to arrest the return of the hammer assembly 55 is a back check 80 suspended from the whippen 18. In this way, by configuring the catcher 78 and the back check 80 in the manner depicted to permit an overlapping of these members, it will be readily seen that there will be no abrupt stopping of the hammer assembly and that said assembly is free to move forward once again when the whippen 18 is permitted to move downwardly from the position shown in Figure 2 for then the back check releases its grip on the catcher, this occurring when the key 12 is released and begins to move upwardly.

Turning now to the operation of the piano action, it will be observed from Figure 1 that the J-shaped end 46 of the jack 40 engages in the notch 68 during this "at rest" position, and, as thus illustrated, the jack is conditioned for transmitting a tone-producing blow to the hammer assembly 55. When the key 12 is depressed at its right end, the key rocks about the balance rail 20 to raise the end 14 thereof up and the upward movement of said end 14 lifts the capstan screw 16 to pivot the whippen 18 in a counterclockwise fashion. Of course, the pivoting of the whippen exerts a lifting force on the jack 40, since the jack is suspended from the whippen by means of the pivot pin 42.

As the jack is moved upwardly, the extremity 48 of the J-shaped end is forced against the butt 60 and such engagement produces a counterclockwise rotation of the butt resulting in the head 56 imparting a tone-producing blow to the sounding string 10. The extremity 48 remains in engagement with the notch 68 throughout this lifting action until disengagement is effected by a counterclockwise rotation of the jack 40, the notch 68 insuring against any premature or accidental deflection of the jack. To produce the counterclockwise disengaging motion at the appropriate time, the projection 44 strikes the regulating screw 52, and once the projection 44 is arrested in its movement, it will be easily seen that the extremity 48 is moved to the right out of engagement with the notch 68. Due, however, to the presence of the inclined nose 70, the lateral movement of the extremity 48 as it is disengaged from the notch 68 provides an additional and final impetus to the butt 60, for the extremity 48 is forced to follow the underside of the nose 70 to produce a quick camming action, thereby causing the butt 60 to be more forcefully moved in its tone-producing direction against the string 10. As stated above, the jack 40 in its upward travel remains firmly engaged with the notch 68 until the precise time that disengagement is desired, it being entirely feasible to adjust the regulating screw 52 to effect this disengagement when the hammer 56 is only one-eighth inch from the string. In this way, not only is power applied to the hammer assembly 55 for a relatively long time, actually almost until the hammer head 56 strikes the string, but the application of power to the head 56 is always for the same interval with the advantage that the tone volume will be identical for the same force applied to the key 12 each time said key is actuated. In other words, the action is always uniform.

During the period that the whippen 18 is being rotated counterclockwise by the key 12, it will be seen that the spool 34 is urged downwardly by the left end of the whippen to pivot the arm 32, the pivoting of the arm 32 of course causing the damper head 28 to be moved away from the string 10 thereby permitting the tone to be sustained for the interval that the key 12 remains depressed. After the hammer head 56 has imparted its blow to the string 10, it rebounds with considerable force, and it is during the rebound travel of the butt 60 that the repetition spring 72 becomes effective for its intended purpose, since the spring is then deflected upwardly to store enough energy for later moving the hammer 56 toward the string 10. The exact amount of spring deflection, and consequently the energy stored therein, depends of course upon the degree of offset or curvature of the section 74, the distance said section 74 is from the pivot point 64 and the strength of the

spring. The choice of these factors is in turn influenced by the size of nose 70, the weight of the hammer assembly, and the distance between the pivot point 64 and the notch 70, all of which should be apparent to a skilled piano technician.

However, before the hammer is again urged toward the string, the catcher 78 engages the back check 80 as shown in Figure 2 to arrest the rebound travel of the hammer assembly. However, by the time the catcher 78 is stopped by the check 10 80 the desired amount of energy will have been stored in the spring 72. The stored energy in the repetition spring 72 is expended as hereinbefore indicated to move the hammer assembly toward the string 10 once again upon release of the key 15 12. The purpose in doing this, which heretofore has not been made manifest, is to make certain that there will be no obstructive interference between the extremity 48 on the jack 40 and the nose 70 on the butt 60. From Figure 3, which depicts an instantaneous position in the return to the rest position, it can be seen that the nose 70 is raised (because the butt 60 pivots about the pin 64) to an extent sufficient to provide a slight amount of clearance (just enough to assure free 25 passage of the nose) between the extremity 48 and said nose. The downwardly concave section 74, cognizance being had of the aforesaid design factors, is instrumental in producing the necessary amount of forward travel. In practice, although varying with different designs, it is suggested that the hammer head 58 might be moved from a position approximately five-eighths inch from the string 10 to a point approximating one-fourth inch therefrom. In any event, it will be seen that the forward travel should be sufficient to permit re-engagement of the J-shaped end 46 in the notch 68 without restriction.

While the spring 72 produces the desired forward movement of the hammer assembly 55 upon release from the back check, it will be recognized that the jack spring 54 acts in such a manner to move the J-shaped end into re-engagement with the notch 68. Sufficient energy for this purpose is stored in the spring 54 by the initial actuation of the key 12, for when the projection 44 strikes the regulating screw 52 during the actuation of the key the spring 54 will be deflected as the jack is moved counterclockwise and the stored energy in the spring 54 is merely expended when the key 12 is released. Also, it is to be observed that the back check 80 is carried by the whippen 13 and upon release of the key 12 the whippen starts to rotate clockwise from the position shown in Figure 2 toward that pictured in Figure 1, this movement lowering the check 80 so that the catcher 78 can be propelled forwardly by the energy stored in the repetition spring 72.

In conclusion, it will be easily seen that the piano action above described is exceedingly compact, especially since the jack 40 parallels approximately the hammer shank 58. Further, the J-shaped or hooked end 46 always remains in engagement with the notch 68 until the butt 60 has reached a preferred angular position and that the disengagement of the J-shaped end 46 is always at a preselected point. Still further the J-shaped end 46 is permitted to be quickly re-engaged with the notch 68 without interference because of the incorporation of the repetition spring 72 into the piano action. This latter feature of course conditions the entire action so that it will be immediately ready for the next actuation of the key 12. Also, it is to be noted that the advantages above mentioned are attained with mechanism

that is simple, rugged and not apt to get out of order easily. Still further, the repetition spring feature may be used with conventional upright or spinet actions, if desired.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. In a piano action, the combination comprising a pivotally mounted whippen, a piano key for actuating same, a hammer, shank and butt assembly, the butt being pivotally mounted and provided with a generally upwardly-directed notch formed in part by a downwardly and forwardly sloping concave cam face, a jack pivotally supported by said whippen having a substantially J-shaped end portion engageable at its extremity in said notch, and stop means engageable by said jack for rotating said jack relative to said whippen at a preferred angular position of said butt whereby said extremity slides across said cam face and provides an additional impetus to said butt during the disengaging of said J-shaped end from said notch.

2. In a piano action, the combination comprising a pivotally mounted hammer shank butt provided with a generally upwardly-directed notch offset from its pivot point, a hammer and shank supported by said butt for movement toward and away from a piano string, a jack having a lateral projection adjacent its upper end and a substantially J-shaped lower end engageable in said notch, a piano key, a whippen fulcrumed adjacent one end thereof and actuatable adjacent its other end by said piano key, said jack being pivotally supported by said whippen and movable upwardly when said whippen is actuated by said piano key, stop means positioned so as to be engaged by said lateral projection as said jack is moved upwardly by said whippen thereby to effect disengagement of said J-shaped end from said notch at a preferred angular position of said butt and thus when said hammer is a preferred distance from the piano string, means biasing said hammer away from the string, a catcher associated with said hammer shank butt and movable therewith, a back check supported by said whippen and engageable with said catcher on the return movement of said hammer, an elongated spring member carried at one end by said butt, shoulder means on said jack engageable with said spring member to deflect said spring member upwardly and thereby store sufficient energy to move said butt and hammer in a direction toward said string a distance sufficient to permit unrestricted re-engagement of the J-shaped end of said jack in said notch upon disengagement of said back check from said catcher resulting from a release of said piano key.

3. In a piano action, the combination comprising a pivotally mounted whippen, a piano key for actuating said whippen, a hammer, shank and butt assembly, the butt being mounted for rotation about a fixed pivot point and provided with

a generally upwardly-directed notch offset from said pivot point, a jack pivotally supported by said whippen having one end engageable in said notch, means for disengaging the jack from said notch at a preferred angular position of said hammer assembly as said assembly is moved in one direction through the medium of said whippen when said key is operated, a catcher movable with said hammer assembly, a back check controlled by the movement of said piano key to arrest the movement of said catcher as said hammer assembly moves in an opposite direction from said one direction, a spring carried by said hammer assembly, and a shoulder on said jack engageable with said spring to flex said spring and store energy therein responsive to movement of said hammer assembly in said opposite direction, whereby said spring moves said hammer assembly again in said one direction when said key is released to pivot said butt and permit said one end of said jack to reenter said notch.

4. In a piano action, the combination comprising a pivotally mounted whippen, a piano key for actuating said whippen, a hammer, shank and butt assembly, the butt being mounted for rotation about a fixed pivot point and provided with a generally upwardly-directed notch offset from said pivot point, a jack pivotally supported by said whippen having one end engageable in said notch, means for disengaging the jack from said notch at a preferred angular position of said hammer assembly as said assembly is moved in one direction through the medium of said whippen when said key is operated, a catcher movable with said hammer assembly, a back check controlled by the movement of said piano key to arrest the movement of said catcher as said hammer assembly moves in an opposite direction from said one direction, and an elongated resilient element attached at one end to said butt and extending substantially laterally therefrom, said jack having means thereon over which a portion of said resilient element rides to cause deflection of said resilient element as said hammer assembly moves in said opposite direction with a concomitant storing of energy in said resilient element which is expended to move said hammer assembly again in said one direction to an extent sufficient to permit unobstructed re-engagement of said one end of the jack with said notch when said catcher is released from said back check.

5. In a piano action, the combination comprising a pivotally mounted whippen, a piano key for actuating said whippen, a hammer, shank and butt assembly, the butt being mounted for rotation about a fixed pivot point and provided with a generally upwardly-directed notch offset from said pivot point, a jack pivotally supported by said whippen having a lateral projection adjacent its upper end and a substantially J-shaped lower end engageable in said notch, stop means positioned so as to be engaged by said lateral projection for disengaging the jack from said notch at a preferred position of said hammer assembly as said assembly is moved in one direction

through the medium of said whippen when said key is operated, a catcher carried by said hammer assembly for movement therewith, a back check supported by said whippen and movable by said 5 whippen into the path of said catcher to arrest the movement of said catcher as said hammer assembly moves in an opposite direction from said one direction, and an elongated spring element attached at one end to said butt and having a 10 downwardly curved portion near its free end, said jack having a shoulder over which said curved portion rides to cause deflection of said spring element as said hammer assembly moves in said opposite direction with a concomitant storing of 15 energy in said spring which is expended to move said hammer assembly again in said one direction to an extent sufficient to permit unobstructed re-engagement of the J-shaped jack with said notch when said catcher is released from said back 20 check.

6. In a piano action, the combination comprising a sounding string, a pivotally mounted whippen, a piano key for actuating said whippen, a hammer, shank and butt assembly for striking 25 said string to produce a tone, the butt being mounted for rotation about a fixed pivot point and provided with a generally upwardly-directed notch formed in part by a downwardly inclined nose, a spring biasing said hammer assembly 30 away from said sounding string, a jack pivotally supported by said whippen having a lateral projection adjacent its upper end and a substantially J-shaped lower end engageable in said notch, a spring biasing said J-shaped lower end of the jack 35 toward said notch, stop means positioned so as to be engaged by said lateral projection for disengaging the jack from said notch at a preferred spacing of said hammer from the sounding string as said hammer assembly is moved toward said 40 string through the medium of said whippen when said key is operated, a catcher carried by said hammer assembly for movement therewith having a sloping surface, a back check supported by said whippen having a sloping surface engageable 45 with the sloping surface of said catcher as said hammer rebounds from said sounding string, an elongated repetition spring attached at one end to said butt and having a downwardly curved cam portion near its free end, said jack having a shoulder over which said curved cam portion rides to 50 cause deflection of said repetition spring as said hammer rebounds from said sounding string with a concomitant storing of energy in said repetition spring which is expended to move said hammer assembly toward said string again to an extent sufficient to permit unobstructed re-engagement of the J-shaped end of the jack with said notch when said catcher is released from said 55 back check.
